UNITED STATES PATENT OFFICE.

OLIVER H. ARNO, OF WILMINGTON, ASSIGNOR TO THE AMERICAN AUTOMATIC ORGAN COMPANY, OF BOSTON, MASSACHUSETTS.

MECHANICAL MUSICAL INSTRUMENT.

SPECIFICATION forming part of Letters Patent No. 266,071, dated October 17, 1882.

Application filed March 14, 1882. (No model.)

To all whom it may concern:

Be it known that I, OLIVER H. ARNO, of Wilmington, in the county of Middlesex and State of Massachusetts, have invented certain new and useful Improvements in Mechanical Musical Instruments, of which the following is a full, clear, and exact description.

This invention relates to mechanical musical instruments wherein reeds or other sound devices to be sounded by the passage of air through them are permitted or automatically caused to sound in accordance with a prepared music-sheet or strip of perforated paper, which is made to pass through the instrument, and as it so passes to secure the opening and closing through mechanism of valves for the reeds or other sound devices, the "organina," so called, being a well-known instrument of this class.

20 The invention consists, first, in a mechanical musical instrument of the arrangement substantially as hereinafter described, and above the raceway for the perforated music-sheet, of the bellows reed-board having reed-chambers and reeds, valves to the reed-chambers, and mechanism for operating the valves from and by the passage of the perforated music-sheet over its raceway; second, in a mechanical musical instrument, of valves for the 25 reed-chambers severally connected to their operating-levers by rods which are arranged between the reservoir-bellows and the bellows operating in conjunction therewith, all substantially as hereinafter described; third, in 30 a mechanical musical instrument, of levers to operate the valves for the reed-chambers, provided with detachable and adjustable points or tips, through which to bear upon the unperforated portion and to enter into the perforations of the music-strip as it passes through the instrument.

In the accompanying plates of drawings, Plate 1, Figure 1 is a central vertical section from the front to the rear end of the instrument; and Fig. 2 is in part a plan view and a horizontal section on line 2 2, Fig. 1. Plate 2, Fig. 3 is an elevation at the rear end, with the casing at such end removed and some parts broken away and others in vertical section. 45 Fig. 4 is a horizontal section on line 4 4, Fig. 1, Plate 1.

In the drawings, A A represent the boards making the two sides, and B and C are boards respectively making the front and rear ends, all of which are joined in any suitable manner, 55 and, together with the board D, making the top, constitute the casing, and in which the several working parts of the instrument are placed, and as will be now described.

E E are exhaust-bellows, four in number. 60 These bellows are placed horizontally two above and two below a common horizontal board, F, which is secured to the side boards, A, and all have vertical air-passages a leading from them to horizontal air-passages b in 65 the horizontal board F, and these several air-passages open to a common horizontal air-passage, c, which is between the two side boards, A, and has a series of parallel horizontal passages, d, arranged at equal distances 70 apart in a common vertical board, G, secured to the side boards, A, and making one side of a vertical reservoir-bellows, H, that at its upper end has a series of air-passages, f, each leading to a separate vertical reed-chamber, g, of a common reed-board, I, which is at the upper part of the vertical bellows-board G, and preferably made of the same board, although it may be made of a separate piece, as particularly shown, and thus in continuation 75 thereof. Each reed-chamber g has a reed, h, vertically placed therein and across the air-passage through the reed-chamber from the air-passage f, connecting it with the bellows, to the upper open end, k, of said chamber. 80

l is a valve to the upper open end, k, of each reed-chamber g. The valves l are similarly hinged at one end, m, and similarly project at their other end, n, beyond and over one side, o, of the reed-board I in a direction toward the 85 exhaust-bellows, and these several valves all open in an upward direction and close in a downward direction, and in both movements each swings upon the hinge at its end m.

The exhaust-bellows E E are in pairs, and 90 for those of each pair to operate alternately—that is, for the one to open while the other closes, and vice versa—the bellows of each pair are connected together by a rod, p, and one of each pair is connected by a separate pitman-rod, q, to separate crank-arms r of a common horizontal shaft, s, which is located below 100

the exhaust-bellows, and is there arranged to turn in suitable bearings of the side boards, A, and to be driven by a crank-handle, J, outside of one side board A of the casing. The 5 rotation of the crank-shaft s works the exhaust-bellows E, and through them the reservoir-bellows, all substantially as heretofore, the several bellows being otherwise constructed and arranged, as usual, to secure thereby an exhaust of air through the reed-chambers, through the reservoir-bellows, and thence through and out of the exhaust-bellows.

10 t is a gear-wheel, secured to driving-crank shaft s , and meshing with a gear-wheel, u , on a horizontal feed-roller, v , placed below the crank-shaft s , and arranged to turn in suitable bearings of the side boards, A A.

15 w is a horizontal presser-roller, arranged at each end to turn in suitable bearings of a horizontal board, K, which is placed below the feed-roller v , and at its end, toward the front end, B, of the casing, is hung by pivots x to and between the side boards, A, so as to be swung thereon in a vertical direction. The 20 presser-roller w is directly below the feed-roller v , and it is placed in close contact therewith by swinging its carrying-board K toward the feed-roller and then securing the board in such 25 position by catching the hooks y at the rear end, C, of the casing over its pins or studs z . The bearings of the presser-roller are in blocks 30 a^2 , arranged to exert a yielding pressure, and the front end, B, of the casing has an opening, L, through it for the passage of a perforated 35 music sheet or strip, b^2 , of paper from the outside of the casing first to and over the gradually upward-rising upper surface, c^2 , beginning at the hinged end of the board K next to and over the flat upper surface, d^2 , of same board, 40 and thence to and between the feed and presser 45 rollers, and finally out of the casing at the opening M in its rear end, C. This movement of the music-paper is secured by the turning of the feed and presser rollers $v w$, as usual. 50 The upper surface, $c^2 d^2$, of the hinged board K makes the raceway for the music-sheet, and the flat portion d^2 of this raceway has a series 55 of depressions or cavities, f^2 . These depressions or cavities are severally parallel to each other and in lines corresponding to the lines of perforations in the music-strip, one for each 60 line of perforations, and for each of the depressions there is a similar horizontal lever, N. The several levers N are above the perforated 65 paper strip b^2 and between it and the exhaust bellows, and they are arranged in lines parallel with the lines of perforations in the music-sheet and in vertical planes coincident therewith, and are all hung upon a common horizontal 70 fulcrum-pin, g^2 , of a common horizontal rail, O, secured to the side boards, A, and each to turn in a separate guide-groove, h^2 , of said rail. Each lever, preferably, is made of wood, and at its end, toward the feed and presser 75 rollers, it has a vertical metallic stud or pin, l^2 , screwed into it, so as to project from its under

side at an acute angle to the line of travel and in a line with a row of the perforations of the music-sheet, and all so that by the swinging of the lever in the proper direction it can enter into a perforation thereof, and through it into the corresponding recess or depression f^2 of the raceway.

80 m^2 is a bent spring, one for each lever. These bent springs m^2 are all fixed at one end, and at the other end each is arranged to press upwardly against the under side of the front arm of its lever N, and thereby to force the rear arm thereof downward and keep its pin l^2 to a bearing upon the unperforated portion 85 of the music-strip, and to enter it into a perforation thereof when a perforation comes in line therewith. The spring m^2 of each lever N allows the lever to lift at its rear end for its pin to rise from and out of a perforation of 90 the music-strip to and upon an unperforated portion as such a portion comes to said pin.

95 n^2 is a vertical rod, one for each of the levers N. Each rod rests upon the upper side of the front portion of its lever N, and thence it passes upward through a vertical guide-opening, o^2 , (all of which are in a common fixed horizontal rail, Q,) and thence through a guide-opening, p^2 , in the horizontal exhaust-bellows board F, (all of which guide-openings 100 p^2 are arranged between the parallel air-passages d , which connect with the air-passages $a b$ of the exhaust-bellows and with the reservoir-bellows H,) and thence to and against the under side of the over-projecting end of a valve, 105 l , to a reed-chamber, g , of the reed-board. The length of each rod n^2 is such that the valve connected with it will be closed when its lever N comes to a rest, and so long as it has a rest upon an unperforated part of the music-strip, 110 and will be lifted and thus opened when the pin or stud l^2 of its lever N enters a perforation of the perforated strip, and so long as such pin remains therein. These operations of a valve, l —to wit, the closing and opening 115 thereof—are secured in the first instance from the depression of the front portion of its lever N by the elevation of the rear portion thereof and by the elevation of the front portion of its lever by the depression of the rear portion 120 thereof, and the lever in the one case receives its movement because of the passage of an unperforated portion of the music-strip on stud l^2 , working against the force of its spring m^2 , and in the other case because of the passage 125 of a perforated portion of the music-strip and the then action of the spring m^2 .

130 The top board, D, is in two parts, O and P, and one, O, of these parts has a section, R, of glass, which is above and covers the several valves l to the reed-chambers. The part O is hung upon pivots s^2 of the side boards, A, so as to be swung upward thereon, and when in position over the valves l it rests upon the upper side of the other part, P, which in turn rests upon a shoulder, q^2 , of each side board, A A, and is hung upon pivots r^2 of said boards,

so as to be swung upward. In Fig. 1 the two parts of the top board, D, are shown in dotted lines as swung upward.

In the mechanical musical instrument above described all the working parts except the raceway K and presser-roller w are above the perforated music-strip. The reed-board I is in continuation of the vertical bellows-board G, and either may be or may not be made of one and the same piece therewith. The raceway for the music-strip can be swung away, as shown in dotted lines, Fig. 1, thus exposing the levers N and their springs m², so that they can be operated upon or manipulated, as may be desired, and so that the music-strip can be inserted without interfering with the levers; and, again, the upward swing of the top D, as described, leaves the bellows, reeds, and their chambers free to be readily handled and operated upon, as may be deemed best. Furthermore, the tips l² of the valve-operating levers N, as they are secured in place by screwing them into the levers, obviously are capable of being readily attached and detached and adjusted in their projection from the levers, as may be found necessary for the proper operation of the levers.

Although bellows for exhausting air through the reeds has been herein particularly shown and described, it is plain bellows for forcing air through the reeds are capable of the same arrangement, and without change, except the usual change of reeds, and that the valves for the reed-chambers would necessarily either have to be provided with springs for holding them closed against the outward pressure of the air upon them or be rigidly connected to their operating-rods n², and such rods in turn similarly connected to their operating-levers N; but the spring-pressure upon the valves, however, would be most preferable.

Obviously the operating-levers N for the valves may be arranged to be raised by means all as well known, and in this case the raceway-board K may be made stationary.

Having thus described my invention, what I claim, and desire to secure by Letters Patent, is—

1. In a mechanical musical instrument, the combination, with a raceway for the travel of a music-strip, of bellows, reed-board having reed-chambers and reeds, valves for the reed-chambers, and mechanism for operating the valves by means of the traveling music-strip, and severally constructed and all arranged above said raceway and music-strip, substantially as described.

2. In a mechanical musical instrument, a reed-board having reed-chambers and reeds, and valves to said reed-chambers, in combination with rods n², levers N, music-strip l², and bellows E H, said rods n² extending from said levers N through the bellows-board F up to the valves, and all severally arranged together for operation substantially as and for the purpose specified.

3. In a mechanical musical instrument, levers N, having detachable and adjustable studs l², in combination with the perforated music-sheet and the valves of the reed-chambers.

4. In a mechanical musical instrument, bellows E E, communicating with bellows H through a series of air-passages, a b c d, in combination with rods n², moving through guideways P² in the board F, separating the air-passages d, levers N, valves l, reed-chambers g, and reeds h, of a reed-board, I, raceway K, and music-sheet l², all substantially as described, for the purpose specified.

In testimony whereof I have hereunto set my hand in the presence of two subscribing witnesses.

OLIVER H. ARNO.
